[57] CLAIM

The ornamental design for a combined swing-arm clamp and axle clamp for clamping an axle to the swing-arm of a suspension chassis wheelchair, as shown and described.

DESCRIPTION

FIG. 1 is a rear perspective view of a combined swing-arm clamp and axle clamp for clamping an axle to the swing-arm of a suspension chassis wheelchair showing my new design; FIG. 2 is a front elevational view thereof with the rear being a mirror image thereof; FIG. 3 is a right side view thereof with the left side being a mirror image thereof; FIG. 4 is a top plan view thereof; and, FIG. 5 is a bottom plan view thereof.

The broken line in FIG. 1 showing the axle and the swing-arm is for illustrative purposes only and forms no part of the claimed design.
